INVENTOR

Arthur H. Washburn

UNITED STATES PATENT OFFICE.

ARTHUR H. WASHBURN, OF BROCKTON, MASSACHUSETTS, ASSIGNOR OF ONE-HALF TO RALEIGH A. PERKINS, OF SAME PLACE.

ELECTRIC-CURRENT REGULATOR AND DISTRIBUTER.

SPECIFICATION forming part of Letters Patent No. 564,951, dated July 28, 1896.

Application filed May 22, 1896. Serial No. 592,665. (No model.)

To all whom it may concern:

Be it known that I, ARTHUR H. WASHBURN, of Brockton, in the county of Plymouth and State of Massachusetts, have invented a new 5 and useful Improvement in an Electric-Current Regulator and Distributer, of which the following, taken in connection with the accompanying drawings, is a specification.

My invention is embodied in a device by 10 which a number of lights in groups or singly and of different colors may be put in or cut out of circuit by groups or singly and the amount of current may be varied, and although the lamps are all in one system the 15 groups are all under perfect and distinct control. Any number may be regulated at the same time, some being supplied with a full current and others with but a small or no current.

20 The device by which this is accomplished is illustrated in the accompanying drawings, in which—

Figure 1 is a plan showing my device in connection with a diagrammatical sketch, 25 showing lamps in groups and also indicating the resistance device. Fig. 2 is a side elevation of my device.

In the drawings, A represents a base-piece made of slate, marble, or any suitable non-con- 30 ductor.

B and C are cleats firmly attached to the base A. These should also be of good non-conducting material.

D D' D¹⁴ are strips of good conducting ma- 35 terial, as copper or brass, firmly connected to the base-piece A. Each one of these strips D D¹⁴ is connected to a resistance-box R R¹⁴ by wires W W, as shown.

A conducting-bar or electrode G⁸ is mounted 40 upon the two cleats B C and securely attached to the same. This bar G⁸ is connected by the wire G⁷ to one pole of the generator G⁶, as shown.

The bars H I J K L are made similar to the 45 bar G⁸ and are firmly attached to the cleats B C. All of the above-mentioned bars are attached to the cleats B C and are insulated from each other and from the resistance conductor-bars D D¹⁴, as shown in Fig. 2.

50 I am not confined to any system of electric-

light arrangement, but for the sake of illustration I have grouped them as shown in the diagram—that is, I have five rows, six lamps in each row. I have designated the rows as “first,” “second,” “third,” “fourth,” and 55 “fifth.” The lamps may be of any desired colors and arrangement of colors. All of the lamps are connected to the generator or “line” by the wires G G' G² G³ G⁴ G⁵. The groups are severally connected to the conductor-bars H I J K L by the wires H' H², I' I², J' J², K' K², and L' L².

Each of the conductor-bars G⁸ H I J K L has upon it a sliding switch S, by means of which it may be put in electrical connection 65 with any of the resistance conductor-bars D D¹⁴.

I will now briefly state the manner of using my device. We will assume that the lamps in the third group are to be put in circuit and 70 with a moderate amount of resistance. First, the switch S on the bar J is pushed over so as to rest on one of the resistance-bars, D³, for instance. Now the switch S on the conductor-bar G⁸ is placed upon one of the resistance-bars, D⁸, for instance. This will complete the circuit from the lamps in the third group through wire G² G⁵, generator G⁶, wire G⁷, conductor-bar G⁸, resistance-bar D⁸, 75 thence through a part of the resistance R, 80 thence through wire W to bar D³, thence to bar J, wire J' J² to lamps in third group.

It is evident that by using other switches any one of the groups may be put in circuit and with any amount of resistance or all of 85 of the lamps may be put in at the same time or some may have great resistance and others small resistance. In fact all kinds of combinations may be made, giving any color or combinations of colors and any degree of in- 90 tensity.

I claim—

In an electric-current regulator and distributor, a series of insulated resistance-bars each connected with a resistance-box, a conductor-bar connected to the line and located at right angles to the said resistance-bars and adapted to be electrically connected with any of said resistance-bars by a switch, said switch, and a series of bars also at right an- 95 100

gles to the said resistance-bars electrically connected to the lamps as described each having a switch adapted to electrically connect with the said resistance-bars, a generator and 5 an electric circuit substantially as and for the purpose set forth.

In testimony whereof I have signed my

name to this specification, in the presence of two subscribing witnesses, on this 28th day of March, A. D. 1896.

ARTHUR H. WASHBURN.
